[57] **CLAIM**

The ornamental design for a foldable hand truck assembly, as shown and described.

DESCRIPTION

FIG. 1 is a perspective view of the foldable hand truck assembly with a handle member extended and a front tow plate pivoted outwardly;

FIG. 2 is a side elevational view thereof with the opposite side being a mirror image thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view illustrating the foldable hand truck assembly in an extended usage position; and,

FIG. 8 is a perspective view illustrating the foldable hand truck assembly in a compact folded condition.

Fig. 1
